UNITED STATES PATENT OFFICE.

CLAUDE A. WITTER, OF BURNHAM, PENNSYLVANIA.

ROLLS FOR ROLLING STEEL WHEELS AND WHEEL-CENTERS.

1,112,959.

Specification of Letters Patent.

Patented Oct. 6, 1914.

Application filed May 11, 1910. Serial No. 560,645.

To all whom it may concern:

Be it known that I, CLAUDE A. WITTER, a citizen of the United States, residing in Burnham, Mifflin county, Pennsylvania, have ⁵ invented certain Improvements in Rolls for Rolling Steel Wheels and Wheel-Centers, of which the following is a specification.

The object of my invention is to construct rolls for rolling steel wheels and wheel centers in such a manner that the bearing of the roll upon the inner edge of rim and web of the wheel or wheel center can be varied to roll any diameter of wheel or wheel center, with any desired width or thickness ¹⁰ of rim, and the roll for rolling the tread surface of the rim of the wheel can be varied without changing the rolls which act upon the inner edge of the rim and the web of the wheel or wheel center.

²⁰ In the accompanying drawing:—Figure 1, is a sectional view through the peripheral roll and the side bearing rolls and illustrating the wheel in position; and Fig 2, is a view similar to Fig. 1, showing a different diameter of wheel.

²⁵ A is the roll, preferably having a face *a* recessed at *a'* to form the tread and flange of the wheel. The recess can be any depth, which is less than the thickness of rim to be rolled.

B and C are the two side rolling rolls having faces *b* and *c*, respectively, which bear upon the web *d* of the wheel.

It will be noticed that the rolls B and ³⁵ C bear upon the inner edge of the rim of the wheel or wheel center and on the web *d*, but not on the hub *d'* of the wheel or wheel center, and the one function of these two rolls is to compress the web and rim, ⁴⁰ thereby reducing the section of blank and increasing the diameter of wheel or wheel center. In order to provide for wheels of larger diameter, I mount detachable bearing sections B' and C' in the side rolls B and C, respectively, giving rolls B and C a larger bearing surface on web *d*, this being permissible on account of increased size of pressed blank.

⁴⁵ The section B' has a bearing flange *b'* which aligns with the face *b* of the roll and is practically a continuation of it, and it also has a screw threaded extension *b''* which is adapted to a threaded recess *b'''* in the rolls B, and, in order to resist any ⁵⁰ strains, I provide an annular rib *b''* on the section B', which is adapted to an annular

groove in the end of the roll B. In order to prevent the jamming of the section B' with the roll B during the process of rolling, as the pressure on the surface *b'* against the ⁶⁰ web *d* would have a tendency to tighten and strip the threads of the extension *b''* and recess *b'''*, keyways are formed in the threaded extension *b''* and the walls of the threaded recess *b'''* for a key *i*. When the section ⁶⁵ B' is screwed into position it turns with the roll B and forms a continuation of the bearing face *b*, as shown in Fig. 1. There may be any number of these sections as desired, and the width of the bearing face *b'* ⁷⁰ may be varied.

The section C' has a bearing face *c'*, an annular rib *c''*, and a threaded extension *c'''* adapted to a threaded opening *c'''* in the roll *C* and is held in position by a key *i'*.

⁷⁵ As shown in Fig. 2, the sections B' and C' have been removed in order to accommodate a wheel of the smallest diameter.

The rolls B and C have bearing faces *b*, *c*, respectively, which rest against the ⁸⁰ sides *a''* of the roll A, and it will be noticed that there is a clear space between the periphery of the roll A and the enlarged portions of the rolls B and C and that these inclined rolls bear upon the inner edge ⁸⁵ of the rim of the wheel or wheel center and on the web *d*, so that by this arrangement the roll A can be removed and another roll substituted having a different contour or width and depth of recess *a'*, when it is ⁹⁰ desired to alter the size and shape of the wheel or wheel center to be rolled, without changing the rolls B and C.

It will be understood that wheels may vary in the width of the tread and thickness ⁹⁵ of rim, as well as diameter, without affecting the thickness of the web.

By this invention one set of rolls B and C may be used for all sizes of wheels and wheel centers, with all variations as to ¹⁰⁰ width and thickness of rims and web *d*, and all that is necessary is to change the bearing sections B' and C', and, if the tread surface of the wheel is of different width, the peripheral roll A can be changed ¹⁰⁵ to suit.

In the present instance the wheel and wheel center blank is properly formed between the dies in a machine and then introduced in a machine having the rolls as ¹¹⁰ above set forth, the roll A shaping the tread of the wheel or wheel center and the

rolls B and C shaping the inner edge of the rim and rolling the web *d* to any desired thickness.

I claim:—

- 5 A side bearing roller for machines of the character described, said roller having two bearing faces, one back of the other, the rear bearing face being arranged to rest against the sides of the roll which forms
- 10 the tread and flange of the wheel, the forward bearing face being shaped to roll the web of the wheel, said roller having a threaded recess at its outer end, a section having a bearing face forming a continua-

tion of the forward bearing face of the 15 body portion of the roller and having a reduced threaded extension adapted to the recess in the body portion, and an annular tongue on one of said parts extending into an annular groove on the other part. 20

In testimony whereof, I have signed my name to this specification, in the presence of two subscribing witnesses.

CLAUDE A. WITTER.
